UNITED STATES PATENT OFFICE.

CARL NELSON, OF TOLEDO, OREGON.

EXTENSION-TABLE.

1,243,621.

Specification of Letters Patent. Patented Oct. 16, 1917.

Application filed January 12, 1917. Serial No. 141,968.

To all whom it may concern:

Be it known that I, CARL NELSON, a citizen of the United States, and a resident of Toledo, in the county of Lincoln and State 5 of Oregon, have invented an Improvement in Extension-Tables, of which the following is a specification.

My invention is an improvement in extension tables, and has for its object to provide 10 a table of the character specified, wherein the intermediate or filling leaves are sectional, and the sections are hinged together and to the table in such manner that the sections may be folded upon each other 15 and dropped downward within the frame of the table to permit the end sections to close together, and wherein folding legs are provided arranged to unfold when the table is extended to support the ends of the table, 20 and wherein other mechanism is provided for locking the intermediate sections in unfolded position.

Figure 1 is a perspective view of the improved table in closed position,

Fig. 2 is a section on the line 2—2 of Fig. 1,

Fig. 3 is a perspective view of the table extended and with the intermediate leaves partially unfolded,

Fig. 4 is a section on the line 4—4 of Fig. 2.

Fig. 5 is a bottom plan view of the table extended,

Fig. 6 is a perspective view of the hinge connection between the intermediate leaf sections,

Fig. 7 is a section on the line 7—7 of Fig. 6,

Fig. 8 is a section on the line 8—8 of Fig. 2 with the sections in folded position,

Fig. 9 is a section on the line 9—9 of Fig. 5 looking in the direction of the arrows adjacent to the line,

Fig. 10 is a perspective view of the legs 45 detached,

Fig. 11 is a similar view showing the locking mechanism for the intermediate leaf sections, and

Fig. 12 is a perspective view of the hinge 50 for connecting the intermediate sections to the table frame.

In the present embodiment of the invention the table consists of end leaves 1 and intermediate leaves, said end leaves being 55 connected by the usual slides 2, 2^a and 2^b, so that they may be moved apart from each

other to permit the insertion of intermediate leaves, or into contact as shown in Fig. 1 to form a complete table without the intermediate leaves. The table is supported by the 60 usual pedestal 3 which has connected with its upper end a plate 4, the said plate being secured at its ends to the central slide at each side of the table, by means of spacing blocks 5. A substantially rectangular frame 65 6 is connected with the plate, the said frame being secured to the plate at the center of the side members.

Each of the intermediate leaves consists 70 of three sections, namely, a central section 7 and lateral sections 7^a, the lateral sections being hinged to the side members of the frame, while the central section is hinged to the lateral section. Each of the lateral sections of each leaf is connected to the adjacent side member of the frame by means 75 of the hinge shown more particularly in Fig. 12. Each of the said hinges consists of a leaf 8 which is secured to the upper side edge of the frame, by means of screws or 80 the like, and a leaf consisting of two portions 9—9^a. The portion 9^a of each hinge leaf 9—9^a is offset from the leaf 8 and connected thereto by the portion 9, which is at an obtuse angle with respect to the portion 85 9^a. The portion 9^a is secured to the under side of the leaf section by screws or the like, and the leaf 8 and the portion 9^a of the leaf 9—9^a are countersunk in the sections.

It will be noticed from an inspection of 90 Fig. 4 that the upper sides of the frame 6 are spaced below the upper edges of the slides 2, 2^a and 2^b, a distance such that when the sections are turned outwardly to lie upon the slides, the portions 9 of the 95 hinges will space the leaf sections at the proper height to permit the sections to lie in the same plane and in the plane of the top of the leaves 1. The central section 7 of each intermediate leaf is connected 100 to the lateral sections by the hinge construction shown more particularly in Figs. 6, 7 and 8. The said construction comprises plates 10 and 11 which are countersunk in the side edges of the leaves 7 and 7^a. 105 A hinge bar 12 is pivoted at one end to the plate 10 as indicated at 13, and the opposite end is connected to the plate 11 by a lost motion or sliding connection indicated at 14. The arrangement is such that when 110 the lateral sections of an intermediate leaf are turned upward and outward to lie upon

the slides, the central section will be lifted into the plane of the lateral sections, and when the lateral sections are folded inwardly, one upon the other, the central section will be lowered into a position beneath the lateral sections.

Each of the bars 12 before mentioned, is cut away at its upper outer-corner as indicated at 16, to engage a stop pin 17 on the plate 10 to limit the swinging motion of the said bar, with respect to the section 7^a to which it is connected, to cause the bar to swing upwardly at its inner end when the section 7^a is swung upward and downwardly to lift the central section into the plane of the lateral section. Either lateral section may be folded inwardly, and buffers 15 are arranged on the under sides of the said lateral sections to prevent them striking each other, when they are folded. These buffers may be of any suitable material, as for instance, rubber.

The sections of the intermediate leaves are locked at one end to the table, in the same plane and in the plane of the tops of the end sections 1, by means of locking plates 18 on the outer slides 2^b of each side, which engage beneath headed lugs 19 on the lateral sections when the leaves 1 are pressed toward each other after the intermediate leaves have been extended. At the other end of the table the intermediate leaf sections are locked by locking plates 20 which are mounted upon spring plates 21, secured to rigid bars 22 on the section 1 at the said end. These spring plates are so arranged that they may swing inwardly, but are limited in their outward swinging movement by extensions 23 from the blocks, the said extensions fitting the outer faces of the plates. These locking plates engage beneath headed lugs 24 on the sections, the said lugs being similar to the lugs 19 before mentioned.

In order to extend the table from the position of Figs. 1 and 2, the sections 1 are drawn away from each other until they occupy the position shown in Fig. 3. The folded intermediate leaves are now visible and accessible and they are unfolded as indicated in Fig. 3, until all of the sections of the intermediate leaves are in the same plane and in the plane of the tops of the leaves 1. The sections 1 when being extended are withdrawn from each other a slightly greater distance than the aggregate width of the intermediate leaves, in order that the said leaves 7-7^a may be unfolded without interfering with the dowel pins 25 which are on the inner edges of the tops of the leaves 1 and which are adapted to engage openings in the edge of the opposite section when the table is contracted, and to engage other openings 27 in the outermost of the intermediate leaves when the

table is extended. After the intermediate leaves have been unfolded as above mentioned, the sections 1 are moved toward each other slightly, sufficient to engage the dowel pins in the openings in the edges of the intermediate leaves, and the top is in condition for use.

In order that there may be no danger of binding or sticking, due to dampness or the like, between the intermediate leaves, the hinge leaves 8 and 9-9^a are connected in the manner shown in Fig. 12. The portion 9 of the leaf 9-9^a, and the leaf 8 have bearings 28 which are adapted to align and interengage to receive a pintle 29, and it will be noticed that the bearings of the leaves are spaced apart slightly so that the hinge leaves may move slightly with respect to each other, longitudinally of the pintle. Thus should for any reason the leaves bind at their adjacent edges, the outermost leaves may move away from the central leaf to compensate for such binding and to permit the free movement of the leaf sections with respect to each other.

A pair of folding legs is arranged at each end of the table to support the said end when the table is extended. The legs 30 of each pair are secured near their upper ends to a hinge bar 31. This hinge bar is connected by hinges 32 to hinge blocks 33 mounted on the slides 2 at one end of the table, and the slides 2^b at the other end.

It will be noticed from an inspection of Figs. 9 and 10 that each leg is extended above the hinge bar 31 as indicated at 34, a sufficient distance such that the upper end of the extension will engage beneath the top of the adjacent leaf 1 when the legs are unfolded, that is, when they occupy the full line position of Fig. 9. Stop blocks 35 are arranged in position such that when the legs are unfolded in the full line position of Fig. 9, the extensions 34 will engage the said blocks to prevent further swinging movement of the legs outwardly at their lower ends, and a spring lock is provided for each pair of legs for locking the legs in unfolded position.

Each of these locks 36 is in the form of a spring plate secured to the top of the leaf 1, the free end of the plate being bent outwardly away from the top and being spaced apart from the adjacent stop block 35 just far enough to permit the extension, after it is passed over the spring plate, to move in between the free end of the plate and the stop block. It will be evident from the description, that the lock 36 will hold the legs in unfolded position until the said lock is released by depressing the same. The folding legs at each end of the table are automatically folded by the contracting of the table. It will be noticed from an inspection of Fig. 5, that the legs of each pair are in register

and that they are also in register with the side members of the frame 6.

It will be evident that when the intermediate leaves are folded and the sections 1 are moved toward each other, the extensions 34 will engage the ends of the side members of the frame 6, and the said extensions will be forced outwardly swinging the lower end of the legs inwardly and folding the said 10 legs upon the plate 4, as shown in Fig. 2. The legs are also automatically extended when the table sections 1 are moved outward away from each other. This extension is brought about by links 37 each of which 15 are pivoted to the extension 34 of one leg of the pair, and each link passes at its inner end through a loop 38 on the frame 6. The inner end of each link is bent outwardly, as shown at 39, to prevent disengagement of the link, and the links are of such length that when the end leaves 1 are almost fully extended, the lugs 39 will engage the loops 38, and will swing the legs into unfolded position. Thus no attention 20 is required in extending the top to unfold the legs, and it is only necessary to release the spring lock 36 in order that the legs may automatically fold.

It will be noticed from an inspection of 30 Fig. 5, that the spring plates 36 are automatically released by the links 37. Each of these links is provided at its outer end with a cam portion 37^a, which is so arranged that it will depress the spring lock to permit the 35 legs to fold.

When the intermediate or folding leaves are folded, the sections 1 of the table are first drawn away from each other to release the pins. The links 37 are held by the 40 frame, and portions 37^a of the links will depress the springs 36 as the legs are drawn outwardly with the end sections.

I claim:

1. An extension table comprising end 45 leaves having legs, a pedestal, oppositely ar-

ranged series of slides connecting the leaves and the pedestal, a substantially rectangular frame connected with the pedestal between the series of slides, intermediate leaves connected with the frame between the end 50 leaves, each intermediate leaf consisting of a central and lateral sections, the lateral sections being hinged to the side members of the frame to fold outwardly into the plane of the end leaves or inwardly upon 55 the central section, a swinging connection between the lateral sections and the central section of each intermediate leaf for swinging the said section up in the plane of the end leaves when the lateral sections are 60 swung outwardly into the plane of the said end leaves, means in connection with the lateral sections and the end leaves for locking the said intermediate leaves in extended position when the end leaves are moved into 65 contact with the outermost intermediate leaves.

2. An extension table comprising end leaves having legs, a pedestal, oppositely arranged series of slides connecting the leaves 70 and the pedestal, a substantially rectangular frame connected with the pedestal between the series of slides, intermediate leaves connected with the frame between the end leaves, each intermediate leaf consisting of a 75 central and lateral sections, the lateral sections being hinged to the side members of the frame to fold outwardly into the plane of the end leaves or inwardly upon the central section, a swinging connection between 80 the lateral sections and the central section of each intermediate leaf for swinging the said section up in the plane of the end leaves when the lateral sections are swung outwardly into the plane of the said end leaves. 85

CARL NELSON.
